UNITED STATES PATENT OFFICE.

VITA HABIB, NOW BY COURT DECREE VITA HABIB, OF CINCINNATI, OHIO.

HEADGEAR.

Application filed December 12, 1925. Serial No. 75,120.

This invention relates to head gear and has for an object the provision of a novel ventilating structure which may be embodied in hats and caps of all kinds.

5 Another object is to provide an article of this kind which may at times assume a position such as to present the appearance of an ordinary hat or cap and one which may be adjusted to permit a regulated amount of 10 ventilation for the head gear when it is on the head of a wearer.

These and other objects are attained by the means described herein and disclosed in the accompanying drawings, in which:

15 Fig. 1 is a side elevation of a hat embodying the structure of my invention, and shown in an open or ventilated position.

Fig. 2 is a cross sectional view taken on line 2—2 of Fig. 1.

20 Fig. 3 is a top plan view of a cap embodying a structure of my invention, said structure being shown in a partly open position.

Fig. 4 is a cross sectional view taken on line 4—4 of Fig. 2.

25 The head gear of my invention is of a novel ventilated form and may be made of practically any form and material of which hats and caps are ordinarily made, for example any form of a sailor's or college hat 30 as shown in Figs. 1 and 2, the form of a cap as shown in Fig. 3, or in the form of a soft or stiff felt hat. The head gear of my invention comprises a brim portion of any desired shape or form such as 8, or in the case 35 of a cap, it may be without a brim, in which case it may be supplied with a vizor such as 9 or it may take the form of a vizorless cap in which case it would have neither brim nor vizor. The crown structure of my head

40 gear comprises a sweat band 10 and a stationary crown portion 11. The stationary crown portion 11 comprises a plurality of spaced segments 12 and may be cut from a single piece of cloth, felt or the like.

45 A movable crown member 14 is formed similarly to the stationary crown member 11 and comprises a plurality of spaced segments of a size such that the segments 15 may form a closure for the opening between the segments 12 of the stationary crown member.

50 The stationary crown member 11 carries at its free edges the brim or vizor, if used, and also has the sweat band 10 secured thereto. The movable crown member 14 is pivoted at its center to the center of the stationary crown member by means of a pivot 16 and

washer member 17, the pivot having suitable flattened head members 18 to preclude separation of the crown members. The washer 17 serves to support the reduced portions of 60 the segments 15 and to retain them in the shape of the general contour of the crown. Where a lighter or more flexible material is used, a ring member 19, which may be of wire, is secured to the segments of the movable crown member 14 by means of stitches 20 or by any other suitable means. The outer free edges of the movable crown member are passed about a flexible wire ring 21 and secured thereto and this ring is disposed between the sweat band and the stationary crown portion so that it is substantially concealed by the brim of the hat or a strip of material taking the place of a brim and serving to provide a body for the hat exteriorly 70 of the sweat band.

From the foregoing it will be apparent that the segments of the movable crown member may be moved as a unit so as to slide beneath the segments of the stationary crown member, thus providing a head gear which has a plurality of large ventilating openings extending substantially from the brim to the top of the crown. In hot weather or at such times as the wearer may engage in athletic sports, it is desirable to have the head well ventilated and at the same time to have some head gear which will hold back the hair of the wearer. When it is cold and the wearer desires less ventilation for his head gear, he may completely or partially close the crown by rotating the movable crown member about the pivot 16 and thereby close the crown and give it the appearance of an ordinary hat or cap. Lower rivet head 18 serves as a finger piece 95 to rotate the crown.

The head gear of my invention is particularly adapted for use by school boys and college men in that the stationary and movable crown segments may be of material of different colors representing the school or college colors. A school or other emblem may be secured on the outer side of one of the segments of the movable crown member 105 if desired.

What I claim is:

1. In a device of the class described the combination of a stationary crown member having spaced sector shaped apertures 110 therein, a rim member secured to the outer edges of said stationary crown member, a

sweat band disposed interiorly of the stationary crown member, a movable crown member comprising a plurality of spaced sectors disposed interiorly of the stationary crown member and having their outer edges disposed between the stationary crown member and the sweat band, and means for pivotally mounting the crown members together at their centers for permitting rotation of the movable crown member within the stationary crown member for alternately opening and closing the sector shaped apertures in the stationary crown members.

2. In a device of the class described the

combination of a pair of similar crown members having sector shaped slots extending from their centers to their outer edges, a pivot passing through the centers of said crown members and permitting relative rotatory movement thereof in contact with one another and means secured to the crown members for retaining them in position to seat them upon the head of a wearer.

In testimony whereof, I have hereunto subscribed my name this 10th day of December, 1925.

VITA HABIB.
